UNITED STATES PATENT OFFICE.

JAMES HOLAN, OF CLEVELAND, OHIO.

HEATING SYSTEM.

Application filed December 22, 1924. Serial No. 757,390.

This invention relates to heating systems for motor vehicles and particularly to vehicles propelled by water-cooled motors.

It is one of the objects of the invention to provide a heating system for the vehicle that will utilize the cooling water of the motor and the circulating pump of the motor for forcing the water through the system. It is a further object of the invention to provide a heating system that will be especially adapted for use in motor busses and which will efficiently heat the interior of the bus body without detrimentally affecting the operation of the motor. A further object of the invention is to provide a system, of the type referred to, that may be conveniently controlled from the operator's station in the vehicle and which shall include means for closing off the circulation of air through the motor radiator when the cooling water of the motor is being circulated through the heating system.

A further object of the invention is to provide a heating system, of the type referred to, having its parts so arranged as to prevent freezing, either of the heating system or of the regular cooling system of the motor, during severely cold weather.

Other objects of the invention and the features of novelty will be apparent from the following description taken in connection with the accompanying drawings, of which:

Figure 1 is a plan view of the interior of a motor bus, embodying my invention;

Fig. 2 is a side elevation thereof, with certain parts broken away;

Figure 3 is an enlarged fragment of Fig. 1, with certain parts shown in section;

Fig. 4 is an enlarged fragment of Fig. 2; and

Fig. 5 is an enlarged section on the line 5-5 of Fig. 4.

Referring to the drawings, 10 indicates a motor bus body which is provided with the cross seats 11, 12, 13, 14, 15 and 16, for passengers, and a seat 17 for the operator. The motor for operating the vehicle is indicated at 18 and is of the usual water-cooled type, 45 with which there is associated the usual radiator 19, at the front end of the vehicle, the circulating pump 20, the manifold 21 through which the hot water is conveyed from the motor to the upper part of the radiator 19, and the pipe 22, by which the water is conducted from the lower part of the

radiator 19 to the suction side of the pump 20, the connection between the pipe 22 and the pump being made through a T-fitting 23. From the pump 20, the water is discharged 60 into the motor jacket by the pipe 24.

At convenient points in the body 10, and preferably under certain of the seats, I arrange radiators such as are indicated at 25, 65 26 and 27. These radiators being preferably of the type that is commonly known as a wall radiator, which is relatively thin; this type of radiator only taking up very small space vertically and, therefore, being well adapted for installation underneath the seats 70 of the vehicle.

In the connection between the manifold 21 and the top of the radiator, I arrange a 3-way valve 28 and connect with the side of this valve a pipe 29, which extends rearwardly over the top of the motor, then downwardly to the floor of the body and rearwardly along the floor, inside of the body, to the radiator 25. As will be seen from Fig. 5, the valve 28 may be positioned 80 to direct the water from the manifold 21 into the radiator 19, or from the manifold 21 into the pipe 29. The valve 28 is actuated by a lever 30 and when this lever, and the valve 28, are in the positions shown in full 85 lines in Fig. 5, the water will flow from the motor to the radiator 19. When lever 30 is in the dotted line position, shown in Fig. 5, the water will flow from the motor into the pipe 29 and the top of the radiator 19 will 90 be cut off from the manifold 21.

From the radiator 25 the water flows through the pipe 31 to the radiator 26 and then from the latter, through the pipe 32, to the radiator 27. A return pipe 33, conducts 95 the water from the radiator 27 back to the fitting 23, the pipe 33 being arranged just above the floor of the vehicle body. The pipes 22 and 33 are in open communication with the suction side of the pump 20 so that 100 the pump will draw the water either from the radiator 19 or from the radiators within the body, depending upon the position of the valve 28.

The dash is indicated at 34 and a thermometer 105 35, is arranged in the pipe 29, near the dash so that it may be conveniently read by the operator from the seat 17. A handle 36 is connected with the lever 30 and extends through the dash 34 to a point where it may 110 be conveniently operated from the seat 17, the handle being provided with the notches

37 for engagement with the dash to locate the valve 28 in its different positions.

The vent pipes 38, 39 and 40 connect with the radiators 25, 26 and 27, respectively, and 5 with a pipe 41 which extends longitudinally of the body to a point adjacent the seat 17, where it is turned upward and then forward and is provided with a control valve 42, which may be conveniently operated, 10 from the seat 17, to relieve the heating system of air.

In the operation of the system above described, if the valve 28 is in the full-line position, shown in Fig. 5, the water will be 15 circulated from the radiator 19 through the motor jackets and manifold 21 to the top of the radiator 19, whence it descends and is cooled by the air circulated through the radiator, in the usual manner. If the handle 20 36 is then drawn rearwardly to swing the valve 28 through an angle of ninety degrees, the water will then be forced from the manifold 21 into the pipe 29 and from the latter through the radiators 25, 26 and 27, and re- 25 turn to the pump 20 by means of the pipe 33, there being no circulation through the radiator 19 under these conditions. In this manner the hot cooling water of the motor may be utilized to heat the interior of the 30 vehicle body and when the temperature within the body reaches the desired degree, the handle 36 is moved forward to return the valve 28 to the full-line position, shown in Fig. 5, and then the circulation will be 35 through the radiator 19 and there will be no circulation through the heating system in the body.

When there is no circulation through the 40 radiator 19, the water in this radiator will be quickly cooled by the air circulating therethrough, and in very cold weather this might result in freezing up this radiator. To avoid this contingency, I provide means for preventing the circulation of air through 45 the radiator 19, when the valve 28 is set to direct the water from the motor through the heating system of the vehicle body. Such means consists of a series of shutters 43, which are mounted on small horizontal 50 shafts 44, in front of the radiator 19. These shutters are connected together, so as to move in unison, by the side links 45. An actuating rod 46 extends from the upper shutter 43, through the radiator 19 and is then turned 55 upward and connected with the lever 30, so as to move with the latter. By this arrangement the shutters 43 will be in the open position, shown in Fig. 4, when the valve 28 is set to circulate the water through the radi-

ator 19, but when the position of the valve 60 28 is changed to circulate the water through the radiators in the body, the shutters 43 will be lowered and prevent the flow of air through the radiator 19. The operation of the shutters 43 is, therefore, so arranged as 65 to require no attention on the part of the vehicle operator.

It will be noted, from Fig. 2, that the radiators 25, 26 and 27 and the pipes by which water is circulated through these radiators, 70 are located below the level of the valve 28 so that there will be no tendency to force the water out through the overflow from the radiator 19, as would be the case if the radiators 25, 26 and 27 were located above the 75 valve 28. Also by elevating the pipe 41 at the forward end of the body so as to have the valve 42 in a relatively high position, this valve may be left open practically all of the time without danger of the water being forced out through the vent pipe. This will prevent any accumulation of steam in the heating system.

While I have illustrated a particular style of bus body and arrangement of radiators 85 therein, it will be understood that these details are subject to change to suit the style of body to which the invention is applied and such changes are intended to be within the scope of the invention, which is defined 90 in the appended claim.

Having thus described my invention, what I claim is:

In a motor vehicle having a water-cooled motor, a radiator, a circulating pump and 95 system of connections whereby the water is circulated through the motor and radiator, the combination of a radiator in the body of the vehicle, a pipe for supplying hot water to the last-mentioned radiator connected 100 to said circulating system at a point between the motor and the first-mentioned radiator, a valve at said point for directing the hot water from the motor either to the first-mentioned radiator or to said pipe, a return pipe 105 from the second-mentioned radiator to the connection between the first-mentioned radiator and said pump, means for shutting off the flow of cooling air through the first-mentioned radiator, and operating means for 110 said valve and the last-mentioned means extending into said body to a point accessible from the operator's station therein and whereby the flow of air through the radiator may be interrupted when said valve is 115 positioned to direct the water into said pipe.

In testimony whereof I affix my signature.
JAMES HOLAN.
